UNITED STATES PATENT OFFICE.

HARRY A. HOLLOWAY, OF ST. JOSEPH, MISSOURI, ASSIGNOR TO THE KING MANUFACTURING COMPANY, OF ST. JOSEPH, MISSOURI, A CORPORATION OF MISSOURI.

DESIGN FOR A LAMP-FIXTURE.

56,163.

Specification for Design.

Patented Aug. 24, 1920.

Application filed February 27, 1920. Serial No. 361,662. Term of patent 3½ years.

To all whom it may concern:

Be it known that I, HARRY A. HOLLOWAY, a citizen of the United States, resident of St. Joseph, county of Buchanan, and State of Missouri, have invented a new, original, and ornamental Design for a Lamp-Fixture, of which the following is a specification, reference being had to the accompanying drawings, forming part thereof.

The figure is a side view of a lamp fixture, showing my new design.

I claim:

The ornamental design for a lamp fixture, as shown.

HARRY A. HOLLOWAY.
